UNITED STATES PATENT OFFICE.

HARRY H. HIPWELL, OF PITTSBURGH, PENNSYLVANIA.

FLASHLIGHT-BATTERY.

1,398,518.

Specification of Letters Patent. Patented Nov. 29, 1921.

Application filed November 16, 1920. Serial No. 424,525.

To all whom it may concern:

Be it known that I, HARRY H. HIPWELL, a citizen of the United States, residing at Pittsburgh, in the county of Allegheny and State of Pennsylvania, have invented a new and useful Flashlight-Battery, of which the following is a specification.

By way of explanation, it may be stated that in the manufacture of cells for flash light batteries, a core is provided, the core being made of manganese, graphite and other chemicals, the core being wrapped in a cover, often made of muslin. After the cover is in place about the core, the common practice, heretofore, has been to tie the cover in place with a piece of thread. The operation which consists in tying the cover in place with a thread, is disadvantageous for a number of reasons. First, the tying with a thread is a slow and tedious process, and it is exceedingly difficult to find operators who can work up sufficient speed, or to train operators to such a speed that the tying operation need not be considered seriously as one of the overhead items in the manufacture of flash light battery cells. Again, in some instances, it is necessary to provide an insulation for the core, and, obviously, a thread does not form an adequate insulation.

The foregoing considerations being understood, this invention aims to provide novel means, in the form of a rubber band, whereby the cover may be held on the core of a flash light battery, and, at the same time, efficient insulation may be afforded.

It is the object of the invention, further, to provide means whereby time may be saved in the securing of a cover on a battery core, the cost of manufacture being decreased accordingly.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the

precise embodiment of the invention shown can be made without departing from the spirit of the invention.

55

In the accompanying drawings:

Figure 1 shows in side elevation, a flashlight battery core whereon the cover is held by the device forming the subject matter of this application, parts being broken away; Fig. 2 is a plan showing one end of the core; Fig. 3 is a plan showing the opposite end of the core; and Fig. 4 is a diagrammatic perspective showing the rubber band as it may appear when mounted on the core.

65

The numeral 1 marks the core of a flashlight battery, the core having a stem 2. A cover 3, sometimes made of muslin, is wrapped transversely around the core 1, the longitudinal edges of the cover being overlapped on each other, as shown at 4. The cover 3 is folded at one end as shown at 5 on the corresponding end of the core 1, about the stem 2, the opposite end of the cover being folded, as indicated at 6, on the corresponding end of the core.

75

In order to hold the cover 3 on the core 1 and to provide adequate insulation, one or more rubber bands are employed, the bands being applied in various ways. Preferably, however, the band is fashioned into any desired number of convolutions 7 surrounding the stem 2 closely, at one end of the core 1. The band is extended, from the convolutions 7, to form a loop, portions of which, indicated at 8, extend transversely of one end of the core 1, adjacent to the stem 2. The sides 9 of the loop extend longitudinally of the core, the bight 10 of the loop extending across the base of the core. One side portion of the loop is crossed on itself, as shown at 11 and is fashioned into any desired number of convolutions 12 which are snapped around the core.

85

The construction is such that the folded ends 5 and 6 of the cover 3 will be held in place, and, at the same time, the longitudinal edges of the cover will be held in overlapped relation as shown at 4.

90

One or more rubber bands may be applied as above described, to a battery core, with great rapidity, the cost of manufacture being decreased. Further, it should be recalled that, when the device forming the

100

subject matter of this application is resort to, an adequate insulation is afforded by the rubber band.

Having thus described the invention, what 5 is claimed is:—

In a device of the class described, a flash light battery core including a stem; a cover surrounding the core; a rubber band formed into a plurality of convolutions surrounding 10 the stem, the said convolutions being extended to fashion a loop disposed longitudi-

nally of the core, one side portion of the loop being crossed on itself and being formed into convolutions surrounding the core transversely.

In testimony that I claim the foregoing as my own, I have hereto affixed my signature in the presence of two witnesses.

HARRY H. HIPWELL.
